(Cl. D44—29)

To all whom it may concern:

Be it known that we, Frank McLaughlin and John E. Roberson, citizens of the United States of America, both residing at New York county, State of New York, have invented a new, original, and ornamental Design for Combination Bottle Opener, Ice Pick, Ice Cracker, and Muddler, of which the following is a specification, reference being had to the accompanying drawing, forming a part thereof and in which

Fig. 1 is a front perspective view of a combination bottle opener, ice pick, ice cracker, and muddler showing our new design.

Fig. 2 is a side elevation thereof; and Fig. 3 is a top plan view thereof.

We claim:

The ornamental design for a combination bottle opener, ice pick, ice cracker, and muddler, substantially as shown.

FRANK McLAUGHLIN.
JOHN E. ROBERSON.
